[57] CLAIM

The ornamental design for a cooking-oil spreader clamp, as shown and described.

DESCRIPTION

FIG. 1 is a top, front, right side perspective view of the cooking-oil spreader clamp showing my new design; FIG. 2 is a rear, right side perspective view thereof; FIG. 3 is a top plan view thereof; FIG. 4 is a left side elevational view thereof, the opposite side being a mirror image; FIG. 5 is a bottom plan view thereof; and, FIG. 6 is a top plan view of an alternate embodiment of FIG. 1, the remaining views being similar to those shown in the first embodiment.

FIG. 1

FIG. 2

FIG. 6

FIG. 3

FIG. 4

FIG. 5
